UNITED STATES PATENT OFFICE.

MAURICE S. ROSENFIELD, OF MORRIS PARK, NEW YORK, ASSIGNOR TO ANELOIS HOLDING COMPANY, INC., OF NEW YORK, N. Y., A CORPORATION OF NEW YORK.

INTERNAL-COMBUSTION ENGINE.

1,193,617.

Specification of Letters Patent.

Patented Aug. 8, 1916.

Application filed August 18, 1913. Serial No. 785,408.

To all whom it may concern:

Be it known that I, MAURICE S. ROSENFIELD, a citizen of the United States, residing at Morris Park, in the borough of the Bronx, city, county, and State of New York, have invented a certain new and useful Improvement in Internal-Combustion Engines, of which the following is a specification.

My invention relates to internal combustion engines and has for its object to provide an improved form of such engine in which the moving parts for controlling the fluid contents of the explosion space during the high pressure strokes of the piston shall be positively acting.

Another object of my invention is to avoid the use of puppet valves; and a further object of my invention is to provide a self contained engine in which all the moving parts, except the shaft, are inclosed.

These and further objects will more fully appear from an examination of the specification, claims, and accompanying drawings taken together or separately.

My invention is illustrated in the drawings and described in the specification and claims, in which the same parts are designated by similar reference characters in all of the figures.

Figure 1 is a horizontal sectional view taken on the line 1—1 of Fig. 2. Fig. 2 is a longitudinal sectional view taken on the line 2—2 of Fig. 1. Fig. 3 is a cross sectional view taken on the line 3—3 of Fig. 2. Fig. 4 is a detail view of a cam. Fig. 5 is a detail sectional view of the follower. Figs. 6 and 6^a are diagrams of the parts at the beginning of the suction stroke. Figs. 7 and 7^a are diagrams of the parts shortly after the beginning of the compression stroke. Figs. 8 and 8^a are diagrams of the parts shortly after the beginning of the working stroke. Figs. 9 and 9^a are diagrams of the parts shortly after the beginning of the scavenging stroke. Fig. 10 is a sectional view of a modification. Fig. 11 is a sectional view of another modification, and Fig. 12 is a view illustrating the development of the slot 18.

In carrying out my invention I employ telescoped or concentric cylinders, the outer cylinder of which is stationary, and the inner cylinder moves or oscillates in relation thereto. The movable element controls the inlet to and the exhaust from the cylinder

and confines the explosion to the piston. The piston moves coaxially with respect to the movable element and is connected therewith for imparting rotary movement thereto relatively to the stationary cylinder. The stationary cylinder has ports which at stated intervals communicate with that portion of the movable cylinder above the piston and at other times are masked.

In the drawings 1 represents a stationary cylinder, provided with the cooling means, and having an inlet port 2 and an outlet port 3. The cylinder is provided with a water jacketed head which carries a spark ing device of any well known form.

Concentrically disposed within the cylinder 1 and in close contact therewith is a movable cylinder 4 provided with an inlet port 4^a and an exhaust port 4^b, and working within this cylinder is a piston 5. The piston carries a pin 6 to which a piston rod 7 is secured by means of a knuckle joint 8. The piston rod is connected to the crank 9 in a shaft 10 which is journaled in bearings 11 in a crank case 12.

The crank bearing for the piston rod is provided with an internally threaded socket 13 having a counter bore in its bottom. The lower end of the piston rod has a peripheral groove 14. A split ring 15 is placed in the peripheral groove 14 and rests upon the bottom of the socket. A nut 16 which surrounds the lower end of the piston rod, is screwed down into the socket and resting on the split ring 15 securely holds the piston rod in position.

Slidably mounted on the piston rod is a sleeve 17 which is provided on diametrically opposite sides with inclined slots 18—18, and playing within these slots are anti-friction rollers carried on a pin 19 on the piston rod. The sleeve 17 carries, at diametrically opposite points, depending arms 20, 20 and the lower ends of these arms have followers 21, 21 which engage the slots in cams 22—22 carried on the crank arms.

The lower end of the movable cylinder 4 is provided with oppositely disposed depending arms 23, 23 each provided with an elongated slot 24 in which play rollers 25 are carried on extensions 26 on the piston 5.

When the shaft 10 is rotated it will carry the cams 22, 22 with it; and the sleeve 17, on account of its engagement with the cam, will be moved longitudinally of the piston.

rod and the piston and its rod will be oscillated by means of the engagement of the rollers on the pin 19 with the inclined slots 18, 18 in the sleeve. The engagement of the 5 rollers 25, 25 with the slots 24, 24, will cause the movable cylinder to oscillate and thereby close and open the inlet and exhaust ports 2 and 3 in proper order.

The lower edge of the movable cylinder 4 10 is supported upon a ledge 27 on the crank casing and this ledge is cut away at 28 to allow for the movement of the arms 23.

Referring more particularly to the devices 15 for oscillating the cylinder 4, I will now proceed to describe the cams 22 and their connection with the cylinder. The follower 21 is preferably composed of a spindle shaped body 29 and a roller 30 both rotatably mounted on a pin 31 carried on the 20 lower end of the arm 20. The follower lies in the slot of the cam 22 and as the cam is rotated the follower is moved toward and away from the center of the cam.

When the piston is in its outermost position 25 after scavenging, as shown in Figs. 6 and 6^a, the follower will lie in the outside groove 32 of the cam. The momentum of the fly wheel will turn the engine over to make the suction stroke and the cam will be 30 rotated in the clockwise direction. This will keep the follower in the groove 32 during the complete suction stroke while the crank is moving through an arc of 180° and maintain the movable cylinder with its inlet 35 port coincident with the inlet port of the cylinder 1. When the piston has completed the suction stroke the cam has moved 180° relatively to the follower which stands at a point on the cam diametrically opposite the point 40 it occupies at the beginning of the suction stroke. Further movement of the cam and crank will start the compression stroke, and at the same time the follower will strike the rise 33 and be shifted through the opening 45 35 into the inside groove 34. This movement toward the center of the cam will draw the sleeve 17 down on the piston rod and the engagement of the slots in the sleeve with the pin on the rod will oscillate the 50 piston and cylinder 4 and mask both the ports 2 and 3. The follower will remain in the groove 34 for a complete revolution thereby keeping both ports closed during the compression stroke as shown in Figs. 55 7 and 7^a and the working stroke as shown in Figs. 8 and 8^a.

When the cam has made a complete revolution with the follower in the groove 34 and the piston has completed its working stroke, 60 the follower will be shifted back through the opening 35 into the intermediate groove 36 thereby oscillating the cylinder 4 backward to bring its port 4 into coincidence with the port 3, while keeping the port 2 closed as shown in Figs. 9 and 9^a, whereby

the up stroke of the piston will scavenge the cylinder.

While I have shown the engine equipped with two cams 22 it will be understood that, only one may be used, if desired, without departing from the invention.

In the modification shown in Figs. 10 and 11 the movable cylinder is omitted and in its place a skirt 37 is carried by the piston. Extending through the piston and along the 75 skirt is a port 38 which may be brought into alignment with either the inlet port 2^a or exhaust port 3^a in the lower part of the cylinder 1. The ports 2^a and 3^a are elongated axially with respect to the cylinder so 80 that the port 38 may communicate with them during the movement of the piston. The skirt is made long enough to close the port during the up stroke of the piston.

The operation of my improved device is 85 as follows: The piston is at the top of its stroke, see Figs. 6 and 6^a, the follower 21 has just entered the groove 32 in the cam 22 and the port 4^a in the movable cylinder 4 has been brought into coincidence with the inlet 90 port 2 of the cylinder 1. The crank is given a movement in the clockwise direction and the piston descends drawing into the cylinder the proper mixture of vapor and air from the carburetor.

When the crank has moved 180° the follower strikes the rise 33 in the groove and is shunted into the innermost groove 34 thereby drawing the sleeve 17 downward along the piston rod and the engagement of the 100 cam slots 18 with the pin 19 will oscillate the piston rod and with it the piston and the cylinder 4 see Figs. 7 and 7^a and close the port 2. The piston will now make its up stroke compressing the mixture in the upper part of the cylinder. The charge is then exploded in the well known manner, driving the piston down, the follower remaining in the groove 34 and holding the cylinder 4 in position to close the ports 2 110 and 3 as shown in Figs. 8 and 8^a.

When the piston reaches the bottom of the working stroke, the follower will be expelled from the groove 34 into the intermediate groove 36, this will cause the cylinder 115 to swing back and disclose the exhaust port 3 through the port 4^a while still keeping the port 2 closed, see Figs. 9 and 9^a. The momentum will carry the piston up thereby expelling the products of combustion from the 120 cylinder and, when the piston reaches its upper limit, the cylinder 4 will be oscillated, by the follower entering the cam 32 to close the port 3 and open the port 2 and the operation will be repeated.

In accordance with the provisions of the patent statute, I have described the principle of my invention together with the apparatus, which I now consider to represent the best embodiment thereof, but I desire to 125

have it understood that the apparatus shown is merely illustrative, and that the invention can be carried out in other ways.

Having now described my invention, what I claim as new and desire to secure by Letters Patent is:

1. An internal combustion engine comprising a stationary cylinder, having a port, an oscillating piston, a second cylinder movable relatively to the first cylinder, and means for oscillating the second cylinder to govern the port.
2. An internal combustion engine comprising a stationary cylinder, having a port, an oscillating piston, a second cylinder disposed between the stationary cylinder and the piston, and means for oscillating the second cylinder to govern the port.
3. An internal combustion engine comprising a stationary cylinder, having a port, an oscillating piston, a second cylinder disposed between the stationary cylinder and the piston, and means for oscillating the second cylinder to govern the port.
4. An internal combustion engine comprising a stationary cylinder having inlet and exhaust ports, an oscillating piston, a second cylinder having a port, and means for oscillating the second cylinder to govern both the inlet and exhaust ports.
5. An internal combustion engine comprising a stationary cylinder having inlet and exhaust ports, a second cylinder, a piston working in the second cylinder, means for oscillating the piston, and connections between the second cylinder and piston whereby the former is oscillated to govern the ports.
6. An internal combustion engine comprising a stationary cylinder having inlet and exhaust ports, an oscillating piston, a piston rod, a crank shaft, a second cylinder carried between the stationary cylinder and the piston and connections between the crank shaft and the second cylinder for oscillating the latter to govern the ports.
7. An internal combustion engine comprising a stationary cylinder having an inlet and an exhaust port, an oscillating piston, a second cylinder having a port and being disposed between the first cylinder and the piston, a cam, and connections between the second cylinder and the cam for oscillating the second cylinder and bringing the port in the second cylinder into register with the inlet port on the suction stroke of the piston and with the exhaust port on the scavenging stroke.
8. An internal combustion engine comprising a stationary cylinder having inlet and outlet ports, a reciprocating piston, a second cylinder carried between the first cylinder and the piston, a piston rod, a crank shaft, a cam on the crank shaft, connections between the cam and the piston

rod for oscillating the piston and connections between the piston and the second cylinder for oscillating the latter.

9. An internal combustion engine comprising a stationary cylinder having inlet and outlet ports, an oscillating piston, an oscillating cylinder, a crank shaft and connections between the shaft and oscillating cylinder whereby the inlet port is opened during the suction stroke, both inlet and exhaust ports are closed during the compression and working strokes and the inlet port closed and the outlet opened during the scavenging stroke.

10. An internal combustion engine comprising a stationary cylinder having inlet and exhaust ports, a piston, a piston rod, a sleeve on the piston rod, a shaft, a cam on the shaft, means for engaging the sleeve with the cam, whereby the sleeve will be reciprocated, means whereby reciprocating motion of the sleeve will impart oscillatory movement to the piston rod, a movable cylinder disposed between the first cylinder and the piston and connections between the piston rod and movable cylinder for rotating the latter.

11. An internal combustion engine comprising a cylinder, inlet and exhaust ports in the cylinder, an oscillating, reciprocating piston, and means, stationary relatively to the reciprocations of the piston, operated by the piston for opening and closing the ports in time with the movements of the piston.

12. An internal combustion engine comprising a cylinder, inlet and exhaust ports in the cylinder, an oscillating, reciprocating piston, means, stationary relatively to the reciprocations of the piston, movable with the piston for opening and closing the ports in time with the movements of the piston.

13. An internal combustion engine comprising a cylinder, inlet and exhaust ports in the cylinder, an oscillating, reciprocating piston, a device oscillating with the piston and engaging the walls of the cylinder and means for moving the device and piston for opening and closing the ports in time with the movements of the piston.

14. An internal combustion engine comprising a stationary cylinder, inlet and exhaust ports in the cylinder, a piston, a movable cylinder between the first cylinder and the piston, connections between the second cylinder and the piston, a crank, a piston rod connecting the piston with the crank, a slotted sleeve on the piston rod, a pin on the rod engaging the slot, and connections between the crank and the sleeve for moving the latter and oscillating the piston and second cylinder.

15. An internal combustion engine comprising a stationary cylinder, inlet and ex-

haust ports in the cylinder, a piston, a crank, a movable cylinder disposed between the first cylinder and the piston, slots in the second cylinder, rollers carried on the piston for engaging the slots, a piston rod connecting the piston with the crank, a slotted sleeve movable on the piston rod, a pin on the piston rod engaging the slot in the sleeve, a follower carried on the sleeve and 10 engaging a cam, said cam being mounted on

the crank whereby the piston and second cylinder may oscillate relatively to the first cylinder during the reciprocations of the piston.

This specification signed and witnessed 15 this 16th day of August, 1913.

MAURICE S. ROSENFELD.
